UNITED STATES PATENT OFFICE.

HENRY L. FRITZE, OF JERSEY CITY, NEW JERSEY, ASSIGNOR OF THREE-FOURTHS TO C. J. HARRINGTON, OF NEW YORK, N. Y.

NON-ARCING CLAMP.

SPECIFICATION forming part of Letters Patent No. 741,785, dated October 20, 1903.

Application filed March 6, 1903. Serial No. 146,471. (No model.)

To all whom it may concern:

Be it known that I, HENRY L. FRITZE, a citizen of the United States, and a resident of Jersey City, in the county of Hudson and State of New Jersey, have invented certain new and useful Improvements in Non-Arcing Clamps, of which the following is a specification.

The object of this invention is to produce a non-arcing clamp which prevents trolley-wheels in overhead electric railroads from pounding and arcing.

The invention consists in an inclined clamp, forming a hood to prevent ice from gathering on the wire, and means to hold the clamp and nurled surfaces to contact with the wire, which prevents it from slipping.

Figure 1 represents the ear or support on which the clamp is used, with the dotted lines showing the outlines of the clamp. Fig. 2 is a side view of Fig. 1, showing the ear or support, the clamp in place, and the wire locked in position. Fig. 3 shows the clamp removed from the ear or support. Fig. 4 is a top view of Fig. 3. Fig. 5 is a cross-sectional view of Fig. 2 on line $x_1 x_2$. Fig. 6 is a cross-sectional view of Fig. 3 on line $x_3 x_4$. Fig. 7 is a cross-sectional view of Fig. 2 on line $x_5 x_6$, and Fig. 8 is a cross-sectional view of Fig. 3 on line $x_7 x_8$.

A in the several figures represents one half of an ordinary wire ear or support employed in overhead-trolley lines for electric-motor cars. It is provided with screw-threaded lugs A', on which the cup-nuts B are screwed to hold the clamps D against the wire C. It is also provided with a groove A³, Figs. 1, 2, and 7, in which the wire C is held, passing through the slot of the screw-posts, as shown at A⁶, Fig. 5, and terminates at A⁴, Fig. 2.

The flange A⁷ is for joining the other section or part of the support.

B', Fig. 5, is a cone-lug formed on the inner top surface of the nut B, which when forced down into the slot A⁶ spreads it and forms a nut-lock.

D in the several figures represents the non-arcing clamp. It is provided with recesses D' for the reception of the screw-posts A' and a longitudinal groove or grooves D³, Figs. 2, 3, 4, 6, 7, and 8, in which the flanges A² of the ear or support rest, as shown in Fig. 7,

which prevents the flanges A² from spreading and also rain or snow from contacting with the wire C. In the groove D³ are located three lugs D⁴, D⁵, and D⁶, Figs. 2, 3, 4, 6, 7, 55 and 8, provided with nurled contact-surfaces D⁷, which by aid of the nuts B are forced against the wire C and which, in conjunction with the bent wire at C', Fig. 2, prevent it from working out of the groove. This clamp 60 is provided with two curved and inclined tracks or surfaces D⁸, Figs. 4 and 8, against which the flanges of the goooved trolley-wheel run, as the wheel leaves the wire C to cross the ear or support A. These inclined surfaces D⁸ are so graduated, as shown by side view at D² in Fig. 3, that no jar or blow is given to the wheel E as it leaves the wire and contacts with the support ear or surface A⁵. The cup-nut B, Fig. 5, prevents snow and ice 70 from forming in the slot A⁶.

I do not limit my invention to a single clamp, as they may be combined with the ears A, having two or more diverging arms, which are employed at switches or crossings. 75

Having thus fully described my invention, what I claim as new, and desire to secure by Letters Patent of the United States, is—

1. The ear or support A having the threaded posts A' and groove A³, in combination 80 with the wire C and clamp D provided with the groove D³ as set forth.

2. The ear or support A having the threaded post A' and groove A³, in combination with the clamp D having groove D³ in which 85 the flanges A² of the support rest and the wire C as set forth.

3. The ear or support A having the threaded post A' and groove A³, in combination with the wire C, clamp D provided with the groove 90 D³ and inclined track D⁸ as set forth.

4. The ear or support A having threaded lugs A' and slot A⁶ and the nut B provided with cone-lug B', in combination with the wire C and clamp D as set forth. 95

Signed at New York city, in the county of New York and State of New York, this 3d day of February, A. D. 1903.

HENRY L. FRITZE.
